UNITED STATES PATENT OFFICE.

FREDERICK A. DILLINGHAM, OF TROY, OHIO, ASSIGNOR TO THE TROY CARRIAGE SUN SHADE COMPANY, OF TROY, OHIO, A CORPORATION OF OHIO.

UMBRELLA TOP-NOTCHER.

1,235,296.

Specification of Letters Patent. Patented July 31, 1917.

Application filed November 6, 1915. Serial No. 59,900.

To all whom it may concern:

Be it known that I, FREDERICK A. DILLINGHAM, a citizen of the United States, and a resident of the city of Troy, in the county 5 of Miami and State of Ohio, have invented certain new and useful Improvements in Umbrella Top-Notchers, of which the following is a full, clear, and exact description, reference being had to the accompanying 10 drawing, forming part of this specification.

My invention relates to umbrella top-notchers, that is to say, to the devices employed in umbrellas to retain the ribs of the umbrella at the top. In top-notchers of 15 the past it has been customary to retain the ribs by hooking them over a ring member supported in some desired manner, and holding the hooked ends over the ring by means of a cover member which was fixed to the 20 umbrella supporting rod. These structures, besides being somewhat inadequate to withstand the strains in a large umbrella, are very troublesome when it comes to repairing the umbrella. The moment the cover 25 member is removed in such top-notchers, the entire set of ribs are released from the ring over which they are hooked. It then becomes a troublesome task to get them all back again, because they all have to be held 30 until the cover member is down.

This difficulty is also present in the assembling of the umbrella, but its greatest inconvenience is apparent when it is necessary to replace one rib which is broken or 35 bent. At such time not only is the task of keeping all the ribs from springing out laborious, but the cover member has to be nailed to the umbrella rod, and the nailing of it back again cannot be done in a very 40 secure and lasting manner.

Accordingly it is the object of my invention to provide a top-notcher in which the ribs are held separately on the common retaining ring, and in which the cover plate 45 has no function except to prevent the rib retaining member from rotating around the umbrella rod.

These objects I accomplish by that certain construction and arrangement of parts to 50 be hereinafter more specifically pointed out and claimed.

In the drawing,

Figure 1 is a central, vertical, sectional view of the top-notcher in place on an umbrella rod.

Fig. 2 is a like view, showing the cover member raised and one of the ribs about to be removed from the top-notcher.

Fig. 3 is a top plan view of the blank from which the device is made, showing several of the tongues bent over.

Fig. 4 is a like view of the same formed up ready for use.

Fig. 5 is a perspective view of the cover member.

Fig. 6 is a side elevation of the parts shown in Fig. 3, except that the tongues are all raised.

1 is the umbrella rod which is cut away at the top to form a shoulder 2 on which the top-notcher is seated. In forming the top-notcher, a blank 3 of metal is cut with a series of radial tabs 4 and stamped out with the central portion of the blank turned up in a series of tongues 5 located between the 70 said tabs. A metal ring 6 is then placed over the blank in a proper machine and the tabs 4 bent around the ring, with the intermediate tongues standing up, adjacent the apertures 7, left in the completed piece by the spaces 75 between the tabs.

The umbrella ribs 8 are bent, as is customary, to form hooks 9 at their upper end and the hooks are hooked over the ring by inserting the ends of the hooks through the 80 slots or apertures 7. The tongues are then bent down, one over each hook and serve to retain each hook permanently on the ring so that they may swing thereon, but so 85 that each hook has a separate retaining tongue.

The top-notcher so formed is set over the umbrella rod so that it rests on the shoulder 2, and it is evident that some means is necessary to prevent it rising up 90 on the rod when the umbrella is in use and to prevent the whole device from turning around on the rod.

For this purpose the cover plate 10 is provided. This plate has a central collar 100 member 11 which is to be tacked in any desired manner to the umbrella rod. It fits down closely over the top-notcher member and is dented in at 12, 12, in several places preferably, so as to engage between 105 several of the bent over tongues. This will stop the rib retaining member from turning around on the rod, and also will prevent the same from rising up off of the shoulder thereof.

It is not believed to be necessary to show the umbrella cover, it being understood that it may be secured over the ribs in any desired manner.

It is evident that the various objects heretofore mentioned are adequately accomplished by the structure now fully described. For removing any rib, it is necessary to raise the cover member and pry up the tongue that retains the rib that it is desired to remove. The rib may then be taken out without disturbing any of the other ribs. Moreover the rib retaining member is not secured to the umbrella rod, and does not have to be unfastened to release it.

It is not desired to be limited in the claims that follow to specific structure where the wording of the claims does not negative a broad interpretation, because there are various equivalent structures which would accomplish the spirit of this invention, which is the providing of a top-notcher which separately retains each umbrella rib.

Having thus described my invention, what I claim as new and desire to secure by Letters Patent, is:—

1. In an umbrella top-notcher, a ring member over which the umbrella ribs are to be hooked, means for mounting said ring, said mounting means having means integral therewith for retaining the ribs on the ring, and a cover member secured to the umbrella to hold said ring mounting means in fixed position thereon.

2. In an umbrella top-notcher, a ring member over which the umbrella ribs are to

be hooked, means for mounting said ring, means for retaining each rib separately on the ring, said means integral with the mounting means for the ring, and a cover member secured to the umbrella to hold said ring mounting means in fixed position thereon.

3. A top-notcher comprising a ring member, a retaining member therefor, having apertures for the insertion of ribs on the ring by hooking them over the same, tongues on the retaining member located adjacent to the apertures, and a cover plate secured to the umbrella and adapted to hold the top-notcher from rising or turning thereon.

4. In an umbrella top notcher, the combination with an umbrella rod, of a ring member over which the umbrella rings are to be hooked, said ring member loosely mounted on the rod, and a cover member rigidly attached to the rod, and having means thereon for maintaining said ring member in non-rotatable position on said rod.

5. In an umbrella top notcher, a metal piece having a series of radial tabs, a ring, said tabs bent around the ring, and tongues adapted to bend down over the spaces intermediate the tabs, for the purpose described.

6. In an umbrella top notcher, a metal piece having a series of radial tabs, a ring, said tabs bent around the ring, and tongues adapted to bend down over the spaces intermediate the tabs, and a cover piece having depressions to fit between the tabs and rigidly mounted on the umbrella.

FREDERICK A. DILLINGHAM.
